Patented May 2, 1916.

UNITED STATES PATENT OFFICE.

GEORGE L. FULK, OF CLEVELAND, OHIO, ASSIGNOR TO THE POSTAL SUPPLY & MFG. CO.,
OF CLEVELAND, OHIO, A CORPORATION OF OHIO.

FOLDING-MACHINE.

1,181,130.

Specification of Letters Patent.

Patented May 2, 1916.

Application filed March 3, 1913. Serial No. 751,674.

To all whom it may concern:

Be it known that I, GEORGE L. FULK, a citizen of the United States, residing at Cleveland, in the county of Cuyahoga and State of Ohio, have invented a certain new and useful Improvement in Folding-Machines, of which the following is a full, clear, and exact description.

This invention relates to a machine for folding of paper or analogous material,—the object being to provide a machine of simple design and construction wherein such material as paper may be folded one or more times without tearing the paper or cracking the surface thereof, the machine being so constructed as to put no tension on the paper to cause it to tear.

Generally speaking, the invention comprises the elements and combinations thereof set forth in the accompanying claims.

Reference should be had to the accompanying drawings forming a part of this specification wherein—

Figure 1 is a side elevation of the folding machine. Fig. 2 is a top plan view of the folding machine. Fig. 3 is a section on the line 3—3 of Fig. 2. Fig. 4 is a section on the line 4—4 of Fig. 2. Fig. 5 is a section on the line 5—5 of Fig. 2. Fig. 6 is a section on the line 6—6 of Fig. 2. Fig. 7 is a section on the line 7—7 of Fig. 2. Fig. 8 is an end view of the middle form shown in Figs. 1 and 2 in the direction of the arrow. Fig. 9 is a section on the line 9—9 of Fig. 2. Fig. 10 is in part an elevation of the second folding form shown in Figs. 1 and 2 looking in the direction of the upper arrow. Fig. 11 is an end elevation showing the end of the first form of Figs. 1 and 2 looking in the direction of the lower arrow. Fig. 12 is a section on the line 12—12 of Fig. 2. Fig. 13 is a section on the line 13—13 of Fig. 2. Fig. 14 shows the folded paper strip in section as it leaves the middle form of the folding machine. Fig. 15 shows in section the strip of paper as it appears finally folded.

In certain classes of work, as, for instance, printed forms wherein it is desired to obtain a number of carbon copies of the original, it is customary to print these strips of paper with the four forms adjacent each other in alinement and perforate the paper between the adjacent printed forms. For convenience in handling, however, it is de-

sirable to fold these forms so that they are in proper position to have the carbon paper placed between their folds that the folded form may be inserted in a typewriter or otherwise written upon. In any event, it has become customary for the printer of such blank forms to supply the paper in folded condition, and further the paper on which the printed matter is arranged is usually printed in the form of continuous strips and in this form they must be folded.

To do the folding by hand is a matter of considerable trouble and usually results in cracking the surface of the paper and otherwise defacing it, so that it becomes objectionable for use. It is therefore the purpose of this machine to receive the paper substantially as it may come from the press and to ultimately deliver the broad strip which is received from the press folded in substantially the manner indicated in Fig. 15. The particular assemblage of forms which are here shown are employed in folding the paper to a four leafed form, but it will be perfectly apparent by employing the features of invention herein disclosed (differently proportioned) that the paper may be caused to be folded any desired number of times.

As herein disclosed the machine comprises three forms which may be generally indicated at 1, 2 and 3, and the paper at the end of the form No. 3 is received between rollers 4 which may be caused to rotate in any suitable manner,—a hand operated reel being shown in the drawing. As the rolls are rotated, they serve as a means for drawing the paper over the forms, by which drawing action the paper is caused to be folded in the manner which is to be described.

Obviously any desired means of effecting the movement of the paper may be employed, and I do not limit myself to the particular means here shown.

Form No. 1 comprises a member having a surface which is broad at one end, as indicated at 5 in Fig. 2, and approaches a point at the opposite end, as indicated at 6. This surface, however, becomes deeper as it approaches the end 6, so that the resultant surface may be said to increase in depth from the end 5 toward the end 6. At the end 6 the form assumes an edge like appearance, as shown in Fig. 11, while at the end

5 it is broad. Reference to Figs. 12 and 13 which are taken upon the lines 12-12 and 13-13 of Fig. 2 will illustrate the decrease of width and increase of height of this surface, from one end to the other.

5 The second form is represented at 2, and may be said to comprise two wall members 7 and 8 which at the end 9 extend parallel with each other, as will be seen in Fig. 10. The upper portion of the wall 7 extends substantially straight, while the lower portion of this wall is bent to assume a direction at the opposite end of the form which is substantially at right angles to the direction of the walls 7 and 8 at the end 9 thereof. The upper portion of the wall 8 bends downwardly and outwardly, and at the end of the form which is opposite to the end 9 it also extends at substantially right angles to the walls 7 and 8 at the end 9 thereof. This results in causing the lower surface of the form to have a generally upward tendency when the forms are placed as shown in the drawing. The lower portions of the walls 7 and 8 are joined together, as indicated at 13, and the paper which is fed between the walls 7 and 8 will in part pass through the slot 14 which is formed by the meeting of the walls 7 and 8, while a certain portion of the paper will lie along that portion of the wall 7 which is not bent. The wall 8 near the forward portion thereof is provided with a guide 15 beneath which that portion of the strip of paper which is in contact with the wall 8 may be guided, and as it passes over the portion of the wall 8 which is opposite from the end 9 of the form, the paper will be caused to assume a horizontal position.

40 The third form has a surface which in part is substantially triangular as is represented at 16. The form also has sides 17 and 18 which meet in an upper ridge indicated at 19,—these walls 18 and 17 at their rear edges are slanting and coöperate with the edges of the surface 16. It will thus be seen that in this form the surface decreases in width from one end toward the other, and through a portion of the length 50 in the same direction, the height increases. The lower edges of the sides 17 and 18 approach each other toward one end of the form and finally meet in what is substantially an end edge. Covering portions of this form are guides such as indicated at 20 and 21. These guides extend over the sides and hold the strip of paper passing over the form so that it will follow the conformation of the walls of the form. The 55 portions of the sides between these covers or guides are provided with troughs, such as indicated at 22, in Fig. 4, which serve to prevent the paper from dropping, and to form a support for it as well.

65 The paper is fed into the machine at the

end of the first form which is indicated at 5. For this purpose there are two coöperating bars indicated at 23 and 24, which form a narrow slot through which the paper passes. The strip passes over the 70 surface of the under side of the form 1, and in so passing it conforms to the surface of this form and any given cross section of the paper would, when arriving at the portion 6 of form 1, be folded in substantially 75 the middle thereof and be extended vertically. The paper thus folded will pass through the opening between the walls 7 and 8 in the end 9 of the second form. One of the leaves of the folded paper will follow the contour of the wall 7, while the other of the leaves will follow the contour of the wall 8, and as the strip of paper emerged from the end 9^a of form 2 it would appear substantially as shown in Fig. 14 80 85 considering the dotted line portion of the fold to represent the paper immediately upon its leaving the second form. As the paper is drawn away from the second form it assumes the position shown in full lines 90 in Fig. 14. As will be seen one-half of one of the folds which was made by form No. 1 has been folded back upon itself. The strip of paper passes in the form shown in Fig. 14 onto the form 3 with the portion of 95 the strip of paper indicated at 25 coming into engagement with the top surface of this form. As the paper passes beneath the guide covers 20 and 21 it will be folded, for these guide covers cause it to conform to the shape 100 of the walls 17 and 18 and as the paper leaves the end of form 3 the leaf which is indicated at 25 in Fig. 14 will be folded back upon itself in the manner indicated in Fig. 15.

105 While I have indicated in the present proportions of the forms shown in this machine that the paper is to be folded into four equal parts, it will be evident that the machine differently proportioned may cause the paper to be folded into three parts by dispensing with form 3, or other folding effects may be obtained as the particular proportions of the design of these forms may be changed. The form indicated at 2 may be made as a continuation of the form 1, if desired, but form 3 should be spaced from form 2 so that the folded material passing from form 2 may come into a flat position to be fed to form 3. If desired, a guide may be provided over which the material may slide in passing from form 2 to 3. Such a guide is indicated at 26 in Figs. 1 and 2.

110 Having described my invention, I claim:

1. In a folding machine, the combination 115 with a plurality of forms through which passes the material to be folded, the first form being shaped to cause the material to be folded to form two leaves, a second form being shaped to cause one of said leaves of 120 125 130

the previously folded material to be folded back upon itself, a third form being shaped to cause the other of said leaves to be folded back upon itself, and means for drawing 5 the material through the forms.

2. In a folding machine, the combination of a form having a surface of decreasing width and increasing depth from one end of the form to the other, a second form having a surface which decreases in depth and increases in width from one end to the other, and a third form which is a surface in part of decreasing width and increasing height from one end toward the other and slanting 10 surfaces which in cross section are inverted V shape, said surfaces being continuations of the first mentioned surface of the third form, and means for drawing the material 15 through the forms.
- 20 3. In a folding machine, the combination of a form having a surface of decreasing width and increasing depth from one end of the form to the other, and a second form in alignment with the first form, said second form having a surface which decreases in depth and increases in width from one end to the other, and means for drawing the material 25 through the forms.

4. A folding form having a straight edge 30 at one end and having an edge at the opposite end, said edge being bent back upon itself and lying at right angles to the first mentioned edge, the surface of the form having a uniform and gradual bending from 35 end to end, a guiding surface for causing a sheet of material to conform with the first mentioned surface.

5. A folding form having a surface which 40 is substantially flat at one end, said surface bending toward the opposite end so that the side edges approach each other and meet at the said opposite end, the end edge at the said opposite end being folded upon itself and extending at substantially right angles 45 to the end first mentioned.

6. A folding form having a surface which 50 is substantially flat at one end, said surface bending toward the opposite end so that the side edges approach each other and meet at the said opposite end, the end edge at the said opposite end being folded upon itself and extending at substantially right angles 55 to the end first mentioned, said folding form having another surface which in part conforms to the first mentioned surface and in part extends away from the first mentioned surface.

7. In a folding machine of the character

described, a folding form having a wall which at one end is straight and at the opposite end is folded back upon itself, the folded edges lying in a plane at right angles to the straight end of the wall, and a second wall which in part conforms to the shape of the first mentioned wall. 60

8. In a machine of the character described, a folding form having opposed surfaces between which the material to be folded is caused to pass, said surfaces extending substantially parallel at one end of the form, 70 one of the surfaces having its longer edges gradually bent away from the other surface until the said edges of said surface meet, the other of said surfaces having one of its edges gradually bent to follow and coincide 75 with an adjacent edge of the first surface.

9. In a folding machine of the character described, a folding form having opposed walls which are substantially parallel at one end of the form, one of the walls being bent 80 so that at the opposite end to that first mentioned the wall is bent back upon itself to form a substantial edge which extends at right angles to the edge where the walls are parallel, the second wall having a free portion and a bent portion which conforms with a portion of the first mentioned wall to form 85 a guiding passageway for the material.

10. In a machine of the character described, a folding form having opposed surfaces between which the material to be folded is caused to pass, said surfaces being close together at one of their ends to form a slot, one of the surfaces being bent so 90 that its forward edge is doubled upon itself, a guide coöperating with said surface to hold the material thereon, the other surface having a portion of its forward edge bent to be parallel with the forward edge of the other surface, said second surface also 100 serving to guide the material, and means for drawing the material through the forms. 95

11. In a folding machine, a folding form having sides which slant and meet in a ridge said sides also converging to meet in 105 an edge at the end of the form the opposite end of the form being formed by a surface which intersects the sides said end surface being of decreasing width from one end to the other end thereof. 110

In testimony whereof, I hereunto affix my signature in the presence of two witnesses.

GEORGE L. FULK.
